UNITED STATES PATENT OFFICE.

WILLIAM B. LONGEST, OF LOUISVILLE, KENTUCKY.

PRIMING MEANS FOR INTERNAL-COMBUSTION ENGINES.

1,207,184.

Specification of Letters Patent.

Patented Dec. 5, 1916.

Application filed December 30, 1915. Serial No. 69,426.

To all whom it may concern:

Be it known that I, WILLIAM B. LONGEST, a citizen of the United States, and a resident of Louisville, in the county of Jefferson and State of Kentucky, have invented certain new and useful Improvements in Priming Means for Internal-Combustion Engines; and I do hereby declare the following to be a full, clear, and exact description 10 of the invention, such as will enable others skilled in the art to which it appertains to make and use the same.

This invention relates to improvements in priming devices for internal combustion engines,—one object of the invention being to provide simple and efficient priming means which will operate to assist in the easy starting of the engine, especially in cold weather.

20 A further object is to provide means for atomizing liquid fuel with air directly into the manifold and in such manner as to avoid projecting the spray against the wall of the manifold and so that atomized fuel and air 25 shall be drawn promptly into the engine cylinder.

With these and other objects in view, the invention consists in certain novel features of construction and combination of parts as 30 hereinafter set forth and pointed out in the claims.

In the accompanying drawings, Figure 1 is a view partly in elevation and partly in section showing one embodiment of my invention, and Fig. 2 is a similar view showing a modified construction.

1 represents the intake manifold of an internal combustion engine; 2 the intake pipe provided with a suitable throttle valve 3, 40 and 4 is a diagrammatical representation of a carburetor.

A comparatively small reservoir 5 may be supported by the intake pipe and for this purpose, the reservoir is provided with a 45 threaded nipple 6 which passes through the wall of the pipe 2. The reservoir is intended to contain gasoline for priming purposes and may be supplied with gasoline from any convenient source of supply, through a pipe

50 7. A valve 8 is provided for the pipe 7 and may conveniently consist of a rod passing through the cover of the reservoir and formed at its lower end to close the inlet of the gasoline pipe 7,—said valve being normally retained upon its seat by the action 55 of a spring 9. The upper end of the valve

rod is made with a groove 10 to receive one arm of a bell-crank 11 pivotally mounted upon the cover of the reservoir, and to the other arm of this bell-crank, one end of a 60 wire 12 is attached,—the other end of said wire being located within convenient reach of the operator to enable him to manipulate the valve 8 when it becomes necessary to replenish the supply of gasoline in the reservoir 5.

A tube 13 passes through and is supported by the nipple 6 and is formed at its inner end with an upwardly projecting member 14 which passes through the cover of the 70 reservoir 5 and is open at its upper end. The free end of the tube 13 is located within the pipe 2 and is made with a nozzle outlet 15 disposed to discharge in line with the bore of said pipe and in a direction toward 75 the intake manifold 1. Another and smaller tube 16 passes through the nipple 6 and its open beveled end 17 projects across the nozzle outlet 15 of the pipe 13, within the intake pipe 2. The other end of the tube 16 80 depends within the reservoir 5 (as at 18) so as to be immersed in the gasoline therein and is provided at a point somewhat below the normal level of the gasoline, with a small hole 19.

When the reservoir is empty, the upper end of the air pipe 13—14 will be closed by a valve 20. This valve is carried by a rod 21 passing through the upright member 14 of the air tube and provided at its lower end 90 with a float 22. When the reservoir is supplied with gasoline, as indicated in the drawing, the float will cause the valve 20 to rise and thus open the member 14 of the air pipe to the atmosphere.

In the construction shown in Fig. 2 the reservoir may be provided with a removable cover 25 and the air tube made to terminate within or at the upper end of the reservoir 100 so as to be open to the atmosphere when the cover 25 has been removed.

When the engine is being started (by cranking in the usual way, or by means of a self-starter) with the throttle valve closed or partly closed, the suction created by the 105 operation of the pistons of the engine will cause air to enter the larger tube 13—14 and to be ejected from the nozzle end 15 thereof into the intake pipe, with considerable velocity, thus causing gasoline to be drawn 110 through the smaller tube 16 and atomized in the intake pipe and in the manifold, from

whence it is immediately drawn into the engine cylinders, (before it can condense within the manifold), and exploded to start the operation of the engine. My improvements afford means for supplying a rich explosive mixture, thus making starting very easy.

A very rich mixture of gasolene and air will be provided until the level of the gasolene descends below the hole 19 in the member 18 of the gasolene tube 16. When said hole 19 becomes exposed, air will enter and thus the richness of the mixture will be reduced,—thus avoiding too rich a mixture after the engine has been started and speeded up.

During the operation of the form of the device shown in Fig. 2, the cover 25 will, of course be removed, but after the engine shall have been started, the cover may be replaced to close the air inlet pipe and to exclude dust.

In the construction shown in Fig. 1, the air inlet pipe will be closed by the valve 20 when the level of the gasolene in the reservoir descends sufficiently after the engine has been started. Should it be found inconvenient to attach my improvement to the intake pipe 2, the same may be attached directly to the manifold, at 23 or 24, Fig. 2, and so disposed that the spray will be projected as indicated by the arrows.

Having fully described my invention what I claim as new and desire to secure by Letters-Patent, is:

1. The combination with the intake of an internal combustion engine, of priming means comprising a liquid fuel reservoir, a liquid fuel tube projecting from said reservoir so as to discharge into said intake, and an air tube having a nozzle opening adjacent to the discharge end of the liquid fuel tube, whereby an atomizer is formed, said liquid fuel tube having a hole somewhat below the normal liquid fuel level in the reservoir.

2. The combination with the intake of an internal combustion engine, of a liquid fuel reservoir having a nipple to enter the intake, two tubes extending through said nipple and having their discharge ends arranged

in permanent and unobstructed atomizer relation to each other, the other end of one of said tubes adapted to enter liquid fuel in the reservoir, and the other end of the other tube being open to the atmosphere.

3. In priming means for an internal combustion engine, the combination with a liquid fuel reservoir, a liquid fuel tube having one end terminating within said reservoir and having its discharge end projecting from said reservoir, an air pipe open at one end to the atmosphere and having a nozzle outlet at its other end disposed at right angles to the discharge end of the liquid fuel tube, forming a permanent, unobstructed atomizer, and means for temporarily closing the inlet end of the air tube.

4. In a priming device for an internal combustion engine, the combination with a liquid fuel reservoir adapted for attachment to the intake of the engine, of a liquid fuel tube and an air tube projecting from said reservoir and having their discharge ends arranged in atomizer relation to each other, the inlet end of the air tube being open to the atmosphere, a valve for closing the inlet end of the air tube, and a float within said reservoir and connected with said valve.

5. In priming means for internal combustion engines, the combination with a liquid fuel reservoir adapted for attachment to the intake of the engine, an inlet pipe for liquid fuel communicating with said reservoir, a spring actuated valve for said inlet pipe, manually operable means for opening said valve, a liquid fuel tube and an air tube projecting from the reservoir and having their discharge ends arranged in atomizer relation to each other, the inlet end of the air tube being open to the atmosphere, a valve for closing said air tube and a float in the reservoir and connected with said valve.

In testimony whereof I have signed this specification in the presence of two subscribing witnesses.

WILLIAM B. LONGEST.
